ELEVATOR CONTROL SYSTEM

Filed Feb. 4, 1929

UNITED STATES PATENT OFFICE

WILLIAM F. EAMES, OF WILKINSBURG, PENNSYLVANIA, ASSIGNOR TO WESTINGHOUSE ELECTRIC & MANUFACTURING COMPANY, A CORPORATION OF PENNSYLVANIA

ELEVATOR CONTROL SYSTEM

Application filed February 4, 1929. Serial No. 337,308.

My invention relates to control systems and has particular reference to control systems for elevators, hoists, and similar motor-driven machinery. In the elevator art, it is 5 desirable that the elevator car be made to accelerate and decelerate as rapidly, and to do so between as wide limits of speed, as is consistent with safety and the comfort of the passengers.

10 Moreover, in modern high speed elevator systems the normal high speed desired is so great that in making floor to floor runs it is impossible to accelerate the car to the high speed and to decelerate the car from the high 15 speed within the distance between adjacent floors. Yet it is desirable that the car should always pass a given point adjacent a floor at which a stop is to be made at a constant speed whether the car is at that instant accelerating 20 from zero speed in making a floor to floor run or is decelerating from the high speed in making a run of a greater distance.

To utilize a single set of accelerating resistors to control the car on floor to floor runs 25 and to control the car on runs of greater distance has been found unsatisfactory since when the resistors are adjusted to attain the high speed operation and accurate deceleration therefrom, the same adjustment of resistors will produce an underrunning or overrunning of the floor for a single floor run.

An object of my invention is to provide a control system for an elevator in which the acceleration and deceleration rates for a 35 short run and for a longer run of the elevator car are capable of independent adjustment to insure accuracy of landing of the car level with the floors whether the car approaches the floor from one floor away there- 40 from or from a greater distance.

Another object of my invention is to provide an elevator system in which the acceleration and deceleration of the car may be so controlled as to attain, whether on a one-floor 45 run, or on a run past a plurality of floors, the maximum speed which may be accelerated to and decelerated from with passenger comfort.

Another object of my invention is to provide acceleration controlling means such that,

having determined the highest intermediate speed to which and from which acceleration and deceleration may be obtained consistent with passenger comfort in making a floor to floor run, and having determined the most 55 desirable rates of acceleration to and deceleration from a higher speed, on accelerating the car from zero speed to its highest speed, or decelerating the car from its highest speed to zero speed, the rates of acceleration and 60 deceleration to the high speed will be substantially the same as the rates of acceleration and deceleration employed on the one floor run.

My invention will be described with reference to the accompanying drawings, where- 65 in:

Figure 1 is a diagrammatic view of my control system, as applied to an elevator system, and

Fig. 2 is a diagrammatic view showing the speed curves obtained with my control system.

Referring to the drawings, I have illustrated, in Fig. 1, an elevator car C suspended in the usual manner by a cable Ca, which passes over a hoisting drum D to a suitable counter-weight Cw. Directly coupled to the hoisting drum D is an armature EM' of an elevator motor EM which is provided with a 75 separately-excited field winding EMF. The armature EM' is connected in loop circuit with the armature G' of a generator G. The generator G is of the cumulative-compound wound type including a series field GSF and a separately-excited field winding GF. A 80 motor M having its armature M' coupled directly to the armature G' of the generator G, acts as a driving means for the generator G. The motor M is illustrated as being of the shunt-wound type having its field winding MF connected in parallel relation to the armature M'.

The illustrated control system is of the automatic landing type wherein the accurate 85 stopping of the elevator car C level with any of the floors served by the car is determined by the operation of suitable inductor relays carried by the car, which cooperate with inductor plates mounted in the hatchway ad- 90 95 100

jacent to each of the floors. The inductor relays illustrated in the present drawing comprise a high-speed up-inductor relay UR5, a high-speed down-inductor relay DR5, an intermediate speed up-inductor relay UR4, an intermediate speed down-inductor relay DR4, a lower intermediate speed up-inductor relay UR3, and a lower intermediate speed down-inductor relay DR3. The final stopping of the elevator car is accomplished through the operation of stopping-inductor relay SR, which operates, as hereinafter described, to deenergize the coil of direction switches 1 or 2, depending upon the direction in which the elevator has been traveling.

For maintaining the motor speed constant under varying loads, the series winding GSF of the generator G is so proportioned that cumulative compounding of the generator is achieved to increase the voltage supplied to the motor under increase in load and to decrease the voltage supplied to the motor under light or overhauling loads in such proportions as to counteract the normal characteristic of the elevator motor to decrease its speed as its load increases.

The direction of rotation and speed of the elevator motor EM are suitably controlled in the usual manner by means of an up-direction switch 1, a down-direction switch 2, a plurality of speed relays 3, 4 and 5, a "transfer" relay 6 and a voltage relay CEMF, which relays operate to include different values of resistance in the separately-excited field circuit of the generator.

In the present case, I have employed two separate resistors HSR and LSR, each divided by ordinary taps into three sections 10, 11 and 12, and 13, 14 and 15, respectively. The resistor HSR is adapted to be included by means hereinafter described in the circuit for the separately-excited generator field only when the elevator car is decelerating from a high speed to zero, and resistor LSR is adapted to be included by means hereinafter described in the separately-excited generator field circuit when the car decelerates after having operated at said intermediate speed.

My invention may best be described with reference to an assumed operation. Assuming the car C to be standing at the lowermost floor, the attendant desiring to start the car upwardly may move the car switch CS in the counter-clockwise direction to energize the "up" direction switch 1 to thereby cause the car to ascend. The "up" direction switch 1 is energized by way of a circuit which extends from line conductor L1 through conductor 16, normally closed contact members 17 of stopping inductor relay SR, conductor 18, the coil of "up" direction switch 1, conductor 19, contact members 20, 21 and 22 on car switch CS and conductor 23 to line conductor L2.

Up" direction switch 1 when energized

completes a circuit for supplying current to the separately excited field winding GF for generator G, which circuit extends from line conductor L1, through conductors 24 and 25, contact members b on "up" direction switch 1, conductors 26 and 27, the field winding GF, conductors 28 and 29, contact members c on "up" direction switch 1, conductors 30 and 31, normally closed contact members b on transfer relay 6, conductors 32 and 33, resistor sections 13, 14 and 15 (comprising low speed resistor LSR) and conductors 34 and 35 to line conductor L2. Upon completion of this circuit the car is caused to accelerate to its lowest or landing speed, as determined by the values of resistors 13, 14 and 15.

The "up" direction switch 1 when energized also completes a self-holding circuit for itself which circuit extends from line conductor L1 through conductor 16 contact members 17 on stopping relay SR to the coil of "up" direction switch 1 as previously described and thence by way of conductor 36, contact members a on "up" direction switch 1 and conductor 37 to line conductor L2. Hence, even though car switch CS should be returned to its "off" position, the car would continue to operate until relay SR was actuated to open its contact members 17 as will hereinafter be described.

To cause the car to travel at a greater speed, the car switch CS may be moved to a further position in a counter-clockwise direction to complete circuits for energizing speed relays 3, 4 and 5, respectively, thereby causing these speed relays to shunt the respective resistor sections controlled thereby from the circuit of the separately excited generator field winding GF.

The circuit for actuating speed relay 3 extends from line conductor L1 through conductors 24 and 38, the coil of speed relay 3, conductors 39 and 40, contact members 41, 21 and 22 on car switch CS and conductor 23 to line conductor L2.

Speed relay 3 when energized completes a self-holding circuit for itself which extends from line conductor L1 through conductors 24 and 38, the coil of speed relay 3, conductor 42, contact members a on speed relay 3, conductor 43, contact members 44 on "up" slow-speed relay UR-3, conductor 45, contact members 46 on "down" slow-speed inductor relay DR-3 and conductors 47 and 23 to line conductor L2.

The circuit for energizing speed relay 4 extends from line conductor L1 through conductors 24 and 49, the coil of speed relay 4, conductors 50 and 51, contact members 52, 21 and 22 on car switch CS and conductor 23 to line conductor L2. Speed relay 4 in turn completes a self-holding circuit for itself which extends from line conductor L1 through the coil of speed relay 4, as previously described, and thence by way of conductor 53, contact

members *a* on speed relay 4, conductor 54, contact members 55 of "up" intermediate-speed inductor relay UR4, conductor 56, contact members 57 on "down" intermediate speed inductor relay DR4 and conductors 58 and 23 to line conductor L2.

The energizing circuit for speed relay 5 extends from line conductor L1 through conductors 24 and 60, contact members of voltage relay CEMF, conductor 61, the coil of speed relay 5, conductors 62 and 63, contact members 64, 21 and 22 on car switch Cs and conductor 23 to line conductor L2. Speed relay 5 in turn completes a self-holding circuit for itself which extends from line conductor L1 to the coil of speed relay 5, as previously traced, and thence by way of conductor 65, contact members *a* on speed relay 5, conductor 66, contact members 67 of "up" high-speed inductor relay UR-5, conductor 68, contact members 69 of "down" high-speed inductor relay DR5 and conductors 70 and 23 to line conductor L2.

While the attendant may move the car switch Cs successively to each of the positions necessary to make contact between contact segment 21 on the car switch Cs, and contact members 20, 41, 52 and 64 respectively to thereby successively energize the "up" direction switch and speed relays 3, 4 and 5 controlled thereby, it is found to be more convenient to permit him to move the car switch to its extreme position immediately without making it necessary for the attendant to exercise care in the precise movement of the car switch handle.

Provision is made, however, for permitting the attendant to select the speed at which the car will operate dependent upon whether he desires the car to stop at the next adjacent floor or at some floor more distant. This selection is achieved by inserting the contact members of voltage relay CEMF in the energizing circuit for high-speed relay 5 and designing relay CEMF so as to pick up only when the voltage supplied to the elevator motor reaches a predetermined value preferably in correspondence with the speed of the car above its landing speed as determined by resistors 13, 14 and 15. In fact the interposition of relay CEMF is for the purpose of delaying the time at which speed relay 5 will be energized for a few seconds and any relay provided with a time delay may be substituted for relay CEMF without changing the operativeness of my system.

Hence, if the attendant moves the car switch to its extreme position and immediately thereafter moves the switch back to its "off" position, speed relay 5 will not be energized and consequently the car will not accelerate to the high speed attained by the exclusion of all of the resistors in circuit with the generator field winding GF. However, if the attendant moves the car switch

to the extreme position and holds the switch in this position until relay CEMF is picked up, speed relay 5 will be energized and the car will accelerate to the highest speed.

It is desirable that the acceleration of the elevator car should be as rapid as possible with comfort to the passengers riding upon the car and for this reason I have arranged my system in such manner that the car will always accelerate upon the low-speed resistors LSR.

To accomplish this purpose, I have provided a transfer relay 6 having its contact members *a* and *b* arranged in the circuits of the low speed resistors LSR and the high speed resistors HSR in such manner as to transfer the generator-field-winding circuit from one of the resistors to the other upon energization or deenergization of the transfer relay.

The circuit for energizing transfer relay 6 is dependent upon the actuation of high speed relay 5 in such manner that the transfer from one set of resistors to the other occurs upon the determination of whether the car is to make a floor to floor run or a run of a longer distance.

Assuming, in the described conditions of operation, that it is desired to have the car travel from the first floor to the third floor (represented by dotted line marked 3rd floor) and that the attendant holds the car switch Cs in the high speed position until relay CEMF picks up, it will be apparent that the car C will accelerate to its highest speed as determined by the application of full line voltage to the generator field winding GF.

Relay CEMF has its coil connected across the loop circuit conductors 71 and 72, respectively connecting opposite terminals of the generator armature G' and the elevator motor armature EM' in such manner that the relay CEMF will be energized when the voltage produced by the generator G builds up to a predetermined value. This actuation of relay CEMF permits high speed relay 5 to pick up as previously described, and by way of contact members *c* on high speed relay 5, a circuit is completed for energizing transfer relay 6 which circuit extends from line conductor L1 through conductors 24 and 73, the coil of transfer relay 6, conductor 74, contact members *c* on high speed relay 5, conductors 75 and 76, contact members *e* on up-direction switch 1, and conductors 77 and 37 to line conductor L2.

Relay 6 closes its contact members *a* to cause the circuit for the generator field winding GF to extend through the contact members *b* controlled by speed relays 3, 4 and 5, while contact members *b* on relay 6 open to exclude contact members *c* of speed relays 3 and 4 from the field winding circuit. It should be understood that, in order that the circuit for the field winding GF for the gener-

ator shall not be open during the transfer period, contact members *a* on relay 6 should be arranged to close just prior to the opening of contact members *b* on this relay.

5 It will be noted that relay 5, having been energized and having closed its contact members *b*, has excluded resistor section 12 from the generator field circuit, and hence the field winding GF will have full line voltage impressed thereon and the car will accelerate to its highest normal speed.

10 After holding the car switch *C_s* in high speed position momentarily, the attendant may return the car switch to off position 15 without interrupting the running of the elevator car, since direction switch 1 and speed relays 3, 4 and 5 will be maintained energized through their respective self-holding circuits. However, centering the car switch 20 will complete a circuit for energizing the actuating coils of inductor relays UR5, UR4, UR3 and SR to cause these relays to be actuated when they pass their respective inductor plates associated with the third floor.

25 The circuit for energizing inductor relays UR5, UR4 and UR3 extends from line conductor L1, conductors 24, 25 and 78, contact members *f* on up-direction switch 1, conductor 79, the coils of inductor relays UR5, UR4 and UR3 in parallel relation, conductors 80, 81, contact members 82, 83, 21 and 22 on car switch *C_s*, and conductor 23 to line conductor L2. The circuit for inductor relay SR extends from line conductor L1, through conductor 84, the coil of relay SR, conductor 85, contact members 86, 83, 21 and 22 on car switch *C_s* and conductor 23 to line conductor L2. Hence, as the car approaches the third floor and successively passes inductor plates 30 UR5', UR4', UR3' and SR', inductor relays UR5, UR4, UR3 and SR will be successively actuated to open their contact members to drop out speed relays 5, 4 and 3, and up-direction switch 1, respectively, to bring the car 35 to a stop at the third floor level.

40 It will be observed that, since the car has been operating at high speed, the deceleration of the car will be caused by the successive insertion of resistors 12, 11 and 10 in the field winding circuit for the generator G to cause the car to decelerate in steps of diminishing speed, each step dependent upon the effective value of the resistance in each of the resistor sections 12, 11 and 10, respectively.

45 Referring to Fig. 2, curves 89 and 91 illustrate the relation of car speed to distance traveled as an elevator car is retarded from high speed to rest. As an illustration, the deceleration is shown as occurring while 50 the car moves the distance between the second and third floors. In the figure, the elevator car is shown operating at full speed, 600 feet per minute, for example, when passing the vertical line marked 2nd floor. At 55 the point 88, the first inductor relay UR5,

passes its associated plate UR5' to thereby open the circuit for high-speed relay 5, inserting resistor section 12 in the circuit of the generator field winding GF. Accordingly, the car decelerates along curve 89 to pass the second inductor relay plate UR4', (this point being represented by dotted line 90). At this time, relay UR4 opens its contact members 55 to drop out speed relay 4, inserting resistor section 11 into the generator field winding circuit, and the car continues to decelerate along the line 91 until the car passes inductor plate UR3', at which time, inductor relay UR3 opens its contact members 44. The opening of the contact members 44 deenergizes speed relay 3, inserting resistor section 10 in the generator field winding circuit, and the car further decelerates until upon passing inductor plate SR', (represented by line 93), relay SR is actuated to drop out the direction switch 1 to bring the car to a stop level with the third floor.

60 It will be apparent that the values of resistor sections 10, 11 and 12 may be suitably adjusted to cause the car to decelerate along any desired curve to make a level stop at the third floor, and once this adjustment is made in an installation, the values of resistance will be proper to make the car land 65 level with the floor each time it is to be stopped thereat.

65 It will be observed that the circuit for energizing transfer relay 6 is controlled by actuation of high speed relay 5, but since 70 it is necessary that the high speed resistors HSR shall remain effectively in the field winding circuit during the entire period of deceleration from high speed until the car is stopped at the floor, I have provided a resistor 87 shunting the contact members *c* of high speed relay 5 in such manner and of such value that while not permitting sufficient current to pass to transfer relay 6 to cause this relay to pick up, it will pass sufficient current to keep transfer relay 6 energized once it has been picked up, even though speed relay 5 thereafter opens its contact members *c*. Hence, speed relay 6 will remain effective to keep the car under the 75 control of high speed resistors HSR until the direction switch 1 (or 2 if the car is traveling downwardly) is opened to bring the car to a stop at the floor.

80 Assuming, however, that the car is standing at the second floor and it is desired to cause the car to make a stop at the third floor, the attendant will move the car switch *C_s* to the running position momentarily and immediately thereafter he will return the switch to off position. In this event, voltage relay CEMF will not have been picked up before the car switch is centered, and hence speed relay 5 will not be energized. Transfer relay 6 will, therefore, remain de- 85

energized and the car will be caused to accelerate on the low speed resistor LSR to attain an intermediate speed determined by the inclusion of resistor section 15 in the field winding circuit (since this resistor section will not be excluded from the circuit). The car will therefore approach the third floor at the intermediate speed until inductor relay UR4 passes its inductor plate UR4', at which time inductor relay UR4 will open its contact members 55 to deenergize speed relay 4 and insert resistor section 14 in the circuit for the field winding, causing the car to decelerate to a slower speed. As the car continues to approach the floor, inductor relays UR3 and SR will be operated in the manner previously described to deenergize speed relay 3 and direction switch 1 to cause the car to decelerate further on resistor 13 and finally to come to rest at the floor level.

Referring to Fig. 2, I have illustrated a curve 94 which represents the deceleration curve of the elevator when it is desired to make a stop on a floor to floor run. As the car passes the point 90 at which inductor relay UR4 passes its inductor plate, deceleration will be initiated and the car will slow down along curve 94 until inductor relay UR3 passes its inductor plate (indicated by dotted line 92), whereupon resistor 13 will be inserted in the field winding circuit and the car will continue to decelerate to make the stop at the floor level.

As was described with reference to deceleration from high speed, resistor sections 13 and 14 may be adjusted to cause the car to decelerate on any desirable speed curve and it will be noted that adjustment of the low speed resistors LSR to fit the condition of a floor to floor run does not in any way disturb the adjustment of the high speed resistors HSR for deceleration from a longer run.

In this way, it is possible that a car, after being installed, may be adjusted to accurately land level with the floors when decelerating from high speed and may also be accurately adjusted to land level with the floor when making a floor to floor run. Also, neither of these adjustments will interfere with the other, since the only time that either the high speed resistors HSR or low speed resistors LSR are effective will be at such times as the car has been so operated as to make the type of run with which the respective resistor is associated.

It is to be understood that the described embodiment of my invention is illustrative only and I do not desire to be limited to any of the details shown herein except as defined in the appended claims.

I claim as my invention:

1. In an elevator control system, an elevator car, motive means therefor, means selectively operable to determine the operating speed of said car, means for decelerating said

car from one of said speeds to zero speed, means for decelerating said car from another of said speeds to zero speed, and means dependent upon the speed selected for rendering the corresponding decelerating means effective. 70

2. In an elevator control system, an elevator car, motive means therefor, means selectively operable to determine the operating speed of said car, adjustable means for decelerating said car from one of said speeds to zero speed, adjustable means for decelerating said car from another of said speeds to zero speed, and means dependent upon the speed selected for rendering the corresponding decelerating means effective. 75

3. In an elevator control system, an elevator car, motive means therefor, means selectively operable to determine the operating speed of said car, voltage modifying means for decelerating said car from one of said speeds to zero speed, voltage modifying means for decelerating said car from another of said speeds to zero speed, and means dependent upon the speed selected for rendering the corresponding decelerating means effective. 80 90

4. In an elevator control system, an elevator car, motive means therefor, means selectively operable to determine the operating speed of said car, resistor means for controlling the deceleration of said motive means from one speed to zero speed, resistor means for controlling the deceleration of said motive means from another speed to zero speed and means dependent upon the selection of speeds by said selecting means for determining which of said resistor means shall be effective. 95

5. In an elevator control system, an elevator car, motive means therefor, means selectively operable to determine the operating speed of said car, a plurality of means for controlling the deceleration rate of said car to zero speed, one for each of a plurality of said speeds and means dependent upon the speed selected for rendering the associated decelerating means effective. 105 110

6. In an elevator control system, an elevator car, motive means therefor, means selectively operable to determine the operating speed of said car, a plurality of independently adjustable resistors for controlling the deceleration rate of said car to zero speed, one for each of a plurality of said speeds and means dependent upon the speed selected for rendering the associated resistor effective. 115 120

7. In an elevator control system, an elevator car operable past a plurality of floors, motive means therefor, means for automatically decelerating said car in steps of diminishing speed to stop said car level with any of said floors, a plurality of means for determining the deceleration rate of said car from a plurality of speeds to zero speed, and 125 130

means dependent upon the operating speed of said car prior to deceleration for determining which of said rate determining means is to be effective.

8. In an elevator control system, an elevator car operable past a plurality of floors, motive means therefor, means for automatically decelerating said car in steps of diminishing speed to stop said car level with any 10 of said floors, a plurality of voltage modifying means for determining the deceleration rate of said car from a plurality of speeds to zero speed, and means dependent upon the operating speed of said car prior to deceleration 15 for determining which of said voltage modifying means is to be effective.

9. In a control system for elevators, an elevator operable past a plurality of adjacent floors, a motor therefor, and means for 20 controlling the power supplied to said motor for selectively operating said motor at a predetermined intermediate speed and a higher speed, means for controlling deceleration of 25 said motor including two separate voltage modifying means, one for decelerating said motor from said higher speed to zero speed, and the other for decelerating said motor between said predetermined intermediate speed and zero speed, and means dependent upon 30 selection of either of said speeds for rendering the corresponding deceleration voltage modifying means effective.

10. In an elevator control system, a car operable past a plurality of floors, motive means 35 therefor, control means for operating said motive means at a plurality of predetermined speeds, including a plurality of deceleration controlling resistors, means for actuating said control means, means operable upon operation of said actuating means to cause said 40 car to operate at one speed for selecting one of said deceleration resistors, and means operable upon actuation of said selecting means for maintaining said selected resistor effective until said car is brought substantially 45 to rest.

11. In an elevator control system, an elevator car operable past a plurality of floors, motive means therefor, control means for said 50 motive means for operating said motive means at a plurality of speeds, including a plurality of deceleration resistors, means for actuating said control means to select the operating speed of said motive means, transfer means 55 for rendering one of said resistors normally effective, and operable to render another of said resistors effective, and means operable upon selection of one speed by said control actuating means for actuating said transfer 60 means.

12. In an elevator control system, an elevator car operable past a plurality of floors, motive means therefor, control means for said motive means for operating said motive 65 means at a plurality of speeds, including a

plurality of deceleration resistors, means for actuating said control means to select the operating speed of said motive means, transfer means for rendering one of said resistors normally effective, and operable to render another of said resistors effective, means operable upon selection of one speed by said control actuating means for actuating said transfer means, and means for maintaining said transfer means in actuated condition until 75 said car is brought substantially to rest.

13. In an elevator control system, an elevator car operable past a plurality of floors, motive means therefor, control means for said motive means for operating said motive means at a plurality of speeds, including a plurality of deceleration resistors, a car switch for actuating said control means to select the operating speed of said motive means, transfer means for rendering one of said resistors normally effective, and operable to render another of said resistors effective, and means operable upon selection of one speed by said control actuating means for actuating said transfer means.

14. In a control system for a motor, a variable-voltage generator for supplying power to said motor, selective means to control the voltage of said generator to determine a plurality of operating speeds for said motor and to decrease the voltage of said generator to retard said motor from any of said operating speeds to a certain speed, said control means comprising resistance means to determine the rate of change of the voltage of said generator throughout retardation of said motor from one of said operating speeds to said certain speed, additional resistance means to determine the rate of change of the voltage of said generator throughout retardation of said motor from another of said operating speeds to said certain speed, and means dependent upon the operating speed selected for rendering the corresponding resistance means effective.

15. In a control system for a motor, a variable-voltage generator for supplying power to said motor, selective means to increase and decrease the voltage of said generator to accelerate and retard said motor between a certain speed and a plurality of higher speeds comprising resistance means to determine the rate of change of the voltage of said generator during acceleration of said motor and throughout retardation of said motor from one of said higher speeds to said certain speed, and additional resistance means to determine the rate of change of the voltage of said generator throughout retardation of said motor from another of said higher speeds to said certain speed, and means dependent upon which of said higher speeds is selected for determining which of said resistance means is to be effective throughout retardation.

16. In a control system for a motor, a vari-

able-voltage generator for supplying power to said motor, selective means to increase and decrease the voltage of said generator to accelerate and retard said motor between a certain speed and a plurality of higher speeds comprising resistance means to determine the rate of change of the voltage of said generator during acceleration of said motor and throughout retardation of said motor from one of said higher speeds to said certain speed, additional resistance means to determine the rate of change of the voltage of said generator throughout retardation of said motor from another of said higher speeds to said certain speed, and means rendered effective by operation of said control means to accelerate said motor to said other higher speed for rendering said resistance means ineffective and for rendering said additional resistance means effective.

17. In a control system for a motor, a variable-voltage generator for supplying power to said motor, selectively operable means to vary the voltage of said generator to accelerate and retard said motor between a certain speed and a higher speed comprising resistance means to determine the rate of change of the voltage of said generator throughout acceleration of said motor between said speeds, additional resistance means to determine the rate of change of voltage of said generator throughout retardation of said motor between said speeds, and transfer means controlled by said selectively operable means for determining which of said resistance means is to be effective.

In testimony whereof, I have hereunto subscribed my name this 31st day of January, 1929.
